LINE MAKING ATTACHMENT FOR
TYPEWRITERS

Edward G. Mosher, Denver, Colo.

Application April 4, 1949, Serial No. 85,372

8 Claims. (Cl. 197—113)

1

This invention relates in general to a line forming attachment for a typewriter, and in particular to an auxiliary attachment mountable on the frame of a typewriter, and including a writing implement such as a ball point type pen which may be moved into or out of engagement with the platen for making lines on the paper carried by said platen.

It is desirable, in many instances, to make vertical and horizontal lines on typewritten work when preparing graphs, charts, illustrations and the like. Although, with most typewriters, one can hold a pen or pencil against a support while rotating or moving the platen horizontally, it is difficult in this manner to make clear cut straight lines as the pen or pencil cannot be held absolutely steady and the pressure is not always constant.

It is the primary object of the invention to provide a line forming device mountable on the typewriter frame and having a writing implement movable into and out of engagement with the platen.

It is another object of my invention to provide a writing implement mounting and adjusting means which will provide considerable latitude in the proper positioning of said writing implement.

It is still another object of my invention to provide a writing implement support which is spring-urged toward the platen to keep a steady pressure between the writing implement and the paper on the platen.

It is one more object of the invention to provide a resilient stop member detachably engageable with the writing implement to prevent contact between the writing implement and the paper on the platen when the lining process is not desired, and also to impart additional pressure on the writing implement when it is performing its lining function.

Further objects and advantages, as well as the construction and operation of my invention will be better understood by reference to the following description in connection with the accompanying drawing in which:

Fig. 1 is a front elevational view of my invention mounted on a typewriter, a portion of the platen only being shown, and the writing implement being positioned clear of the platen.

Fig. 2 is an enlarged, detailed front elevational view of the invention, showing a fragmentary view of the frame on which the device is mounted.

Fig. 3 is an enlarged side elevational view of

the invention, showing a fragmentary view of the platen, the writing implement being shown in line forming position.

Fig. 4 is a fragmentary elevational view of the resilient stop member and the aperture therein.

Fig. 5 is a side elevational view similar to Fig. 3 showing the writing implement moved from line forming position and being held by the resilient stop member from contacting the platen.

Referring now to the drawing by numerals of reference 1 designates a platen on a typewriter and 2 indicates a portion of the typewriter frame.

15 The line forming device comprising my invention has a U-shaped yoke 3 secured to the typewriter frame 2 by suitable fastening members 4. A pair of side links 5 are pivotally mounted to the yoke 3 by pin 6. A spring 7 encircles the pin 6 at one end thereof and has one end 8 secured under one of the fastening members 4 and the other end 9 hooked about one edge of one of the side links 5 for the purpose hereinafter specified.

25 At the upper end of each of the links 5 is carried the pen bar 10, pivotally mounted on threaded screw 11, a large nut 12 providing means for locking the pen bar 10 and pen in adjusted position.

30 The writing implement or pen 13, which may be of the ball point variety, is carried in an opening 13' in the pen bar 10 and is so related to the threaded screw 11 that the threads of the latter will engage the pen to prevent longitudinal movement thereof.

35 I have preferred to use a ball point pen in the embodiment of my invention but I do not want to be limited to any particular form of a writing implement as any suitable means for forming a line may be successfully employed in my invention.

40 A resilient pen engaging member 14 is secured under the yoke fastening members 4 and has a pen insertion opening 15, reduced pen engaging slot 16, and pen holdback slot 17, the use of which will be hereinafter explained. Offset shoulder 18 on the pen acts as a stop.

45 When the device is properly mounted on the typewriter, the spring 7 will urge the links 5 with pen bar 10 and the pen 13 toward the platen.

The resiliency and position of the pen engaging member 14 are such that when the pen abuts the holdback slot 17 the member 14 will prevent the pen from contacting the platen. This position is 55 maintained when the making of lines is not de-

sired. As indicated in Fig. 1, the pen 13 may be swung to a vertical position clear of the resilient member 14 when circumstances make it desirable that the pen be so positioned remote from the platen.

When it is desired to use the pen for forming lines, the nut 12 is released and the pen 13 is swung so that it will coincide with insertion opening 15 in the resilient pen engaging member 14, said member 14 then being manually forced rearwardly until the opening 15 is clear of shoulder 18 on the pen at which time the pen is swung down into the reduced pen engaging slot 16. Pressure on member 14 is released and the nut 12 is tightened to prevent further vertical movement of the pen, which is now being urged toward the platen by spring 7 and by resilient member 14.

Movement of the carriage horizontally will produce horizontal lines. Rotation of the platen will 20 produce vertical lines on the paper.

When the pen is no longer needed for forming lines, nut 12 is loosened and the pen swung up until it coincides with opening 15 at which time the resilient member 14 will move slightly toward the platen due to its inherent resiliency, and the pen can be tilted until it rests in slot 17. The nut can be tightened until it is again desired to use the pen for line forming. It will also be seen that the pen can be tilted to substantially 25 vertical position and held there until needed again for line forming.

From the foregoing it will be apparent that I have provided a relatively simple line forming device for typewriters and the like which may be mounted on the frame of the typewriter and moved into and out of engagement with a paper on the platen. Vertical and horizontal lines can be easily made and the use of a ball point pen will facilitate making lines through a number of carbon copies as considerable pressure can be exerted with such a pen.

The pen, which is a standard unit easily obtainable, can be quickly and easily replaced, thus making for a permanent device available for constant and continuous use.

Although my line forming device has been shown on a typewriter, it is obvious that my invention can be used on a bookkeeping, billing, calculating or similar machine where it is desirable to form lines for various purposes.

It is obvious that changes in form, proportion and details of construction may be resorted to without departing from the spirit of my invention and I reserve all rights to such changes as come within the scope of these specifications and the claims which follow.

What I claim as new and desire to secure by Letter Patent is:

1. A line forming device for typewriters comprising a writing implement, a support for the writing implement, said support being adapted to be carried on the typewriter frame, a spring normally urging the writing implement into writing position, and a resilient member in the path of the writing implement, said resilient member having a plurality of openings therein, the writing implement being adjustably and individually related to the openings in the resilient member, said writing implement when engaged in one of the openings being urged by the resilient member into writing position, when engaged in another opening being freely movable with respect to the resilient member, and when engaged in the third opening being retarded by the resilient 60 member.

member from movement toward writing position.

2. A line forming device for typewriters comprising a writing implement, a support for the writing implement, support securing members holding said support to the typewriter frame, a spring normally urging the support and the writing implement into writing position, and a resilient member carried by the support and positioned in the path of the writing implement, said resilient member having openings therein, the writing implement being adjustably related to the resilient member and the openings therein, said writing implement when in contact with one of the openings being urged into writing position, when received in another opening being freely movable with respect to the resilient member, and when in contact with the third opening being retarded by the resilient member from movement toward writing position.

3. A line forming device for typewriters comprising a writing implement, a yoke carried on the typewriter frame, a writing implement support pivotally carried by the yoke, a spring normally urging the support and the writing implement into writing position, and a resilient member in the path of the writing implement, said resilient member having a plurality of openings therein, the writing implement being adjustably related to the openings in the resilient member, the writing implement being urged toward writing position by the resilient member when in one of the openings, the writing implement being freely movable with respect to the resilient member when in a second opening, and the resilient member retarding movement of the writing implement toward writing position when the writing implement is in a third opening.

4. A line forming device for typewriters comprising a writing implement, a yoke carried on the typewriter frame, a writing implement support pivotally carried by the yoke, a pivot pin passing through the support and the yoke, and a spring encircling the pivot pin and contacting the support and the yoke and normally urging the support and the writing implement into writing position.

5. A line forming device for typewriters comprising a writing implement, a yoke carried on the typewriter frame, a writing implement support pivotally carried by the yoke, a spring normally urging the support and the writing implement into writing position, and a resilient member secured to and extending from the yoke and having openings therein, said resilient member being in the path of the writing implement, the writing implement being adjustably and selectively related to the openings in the resilient member and being urged into writing position, freely movable with respect to the resilient member, or retarded from movement into writing position, depending on the opening to which it is related.

6. A line forming device for typewriters comprising a writing implement, a support for said writing implement, said support including a writing implement bar, the writing implement being adjustably carried by the bar, said bar being pivotally carried in the support, a locking device for securing the bar and the writing implement in adjusted position, a spring normally urging the writing implement and the support into writing position, and a resilient member in the path of the writing implement and having openings therein, the writing implement being

adjustably and selectively related to the openings in the resilient member and being urged into writing position, freely movable with respect to the resilient member, or retarded from movement into writing position, depending on the opening to which it is related.

7. A line forming device for typewriters comprising a writing implement, a support for said writing implement, said support including a writing implement bar, a pin passing through the bar and pivotally relating said bar to the support, and a lock nut on the pin for securing the bar in adjusted position, said writing implement contacting the pin and being retained in adjusted longitudinal position thereby.

8. A line forming device for typewriters comprising a writing implement, a support for said writing implement, said support being adapted to be carried on the typewriter frame, a stop shoulder on the writing implement, and a resilient
